UNITED STATES PATENT OFFICE.

ROYCE L. BEERS, OF DETROIT, MICHIGAN, ASSIGNOR TO DETROIT STOKER COMPANY,
OF DETROIT, MICHIGAN, A CORPORATION OF MICHIGAN.

STOKER.

Application filed January 31, 1927. Serial No. 164,935.

This invention relates to stokers and more particularly to improvements therein, designed to consolidate or unify the exteriorly arranged mechanism of the stoker to thus 5 cheapen the cost of manufacture, facilitate assembly and render more efficient the operation thereof.

It has heretofore been the practice generally, in the manufacture of stokers, to locate 10 the blower fan at the side or rear of the stoker or at some point remote from the fuel feeding mechanism which is customarily arranged at the front of the furnace and to locate a steam engine or other form of power 15 unit somewhere adjacent the stoker and to drive both the fan and the fuel feeding mechanism from this engine. This necessitated the employment of rather extended belts and shafts to drivingly connect the engine with 20 the parts to be operated. In some instances it has been the practice to drive the blower fan by separate motor and in other installations to substitute a motor for the engine to drive both the fuel feeding mechanism and 25 the fan. This mechanism, which is generally termed auxiliary equipment, not only utilized space adjacent to the stoker but necessitated association with and connection to the stoker at several points and has been found to be 30 otherwise unsatisfactory. It is, therefore, one of the primary objects of this invention to provide a compact and unified mechanism wherein a power unit such as an electric motor is arranged to drive both the stoker mechanism 35 and the blower fan which latter part is also arranged at the front of the stoker adjacent to and closely associated with the motor and the fuel feeding mechanism. With such an arrangement it is possible to mount 40 the motor and fan either separately or as a unit upon or adjacent to the front of the stoker and to also connect the shaft of the motor, by means of a short belt or chain to the stoker mechanism.

45 The several objects, advantages and novel details of construction of this invention will be made more apparent as this description proceeds, especially when considered in connection with the accompanying drawings 50 wherein

Figure 1 is a fragmentary perspective view of the front of a stoker showing the application of my invention,

Figure 2 is a longitudinal sectional view through the stoker, partly in vertical section 55 and partly in elevation.

Figure 3 is a fragmentary front elevational view partly in vertical section and partly in elevation taken substantially on the plane indicated by line 3—3 in Figure 2, and 60

Figure 4 is a fragmentary horizontal sectional view through the stoker with the hopper removed and taken substantially on the plane indicated by line 4—4 in Figure 3.

While in the drawings one design of under feed stoker is illustrated somewhat in detail it should be understood that this is for illustrative purposes only so that the application of my invention may be more readily appreciated. It will be obvious, however, that 70 neither the type of stoker nor the details of construction thereof in any manner limit the interpretation of the invention herein involved. In the drawings the reference character 10 indicates the front wall of the stoker, 75 11 a longitudinally extending retort and 12 the tuyères which are supplied with air from an air chamber 13 arranged under the retort. The air chamber opens at the front of the stoker through a passage or opening 14 formed in the front wall 10 of the stoker and is supplied with air under pressure by blower 80 fan yet to be referred to. The reference character 15 indicates a fuel hopper, 16 a fuel feeding ram and 17 a push rod for feeding fuel 85 longitudinally of the retort. The ram 16 is reciprocated by mechanism including a connecting rod 17' and a crank shaft 17" driven through suitable gearing including a reduction gearing contained in the housing 18, the 90 power therefor being applied to shaft 19, in the manner also to be more fully hereinafter referred to.

Mounted adjacent the front wall of the 95 stoker is a power unit here shown as an electric motor 20. This motor may be mounted as for instance by means of supports 21 to a forwardly projecting part 22 of the stoker although obviously the particular manner in which the motor is mounted is of little consequence as obviously it may be mounted directly upon the front wall of the stoker or upon a support immediately in front of this wall. The shaft 23 of the motor is drivingly 100 connected to a blower fan 24 which is connected by conduit 25 to the air passage 14 which 105

- communicates with the air chamber 13 to thus supply air under pressure to this chamber. The shaft 23 of the motor 20 extends outwardly therefrom at the other side thereof and is 5 provided with a sprocket wheel 26 which is connected by means of a chain or the like 27 to a sprocket wheel 28 on the driving shaft 19 of the fuel feeding mechanism, the drive gearing of which is contained in the housing 18 as 10 previously described. Thus it will be seen that the motor 20 is drivingly connected to both the blower fan and the fuel feeding mechanism and is compactly and closely associated therewith.
- 15 The amount of air forced into the air chamber 13 by the blower fan 24 may be controlled by means of a damper 29 arranged in conduit 25 and mounted upon a shaft 30 which extends vertically through a guide bracket 31 to 20 receive on its end a handle 32. By means of this handle the damper may be adjusted and may be secured in place by means of a pin 33 passed through the handle and through one of a series of apertures in bracket plate 31.
- 25 In practice a motor 20 and fan 24 will be associated with each stoker and such motor and fan will preferably be associated with the stoker as a unit. Among the advantages resulting from this construction is the elimination 30 of the long driving shaft which was heretofore used to connect the engine to the several stoker mechanisms and the belt gearing connecting the engine to the fan. Furthermore each stoker, in accordance with the present invention, can be operated as a complete or separate unit and may be individually and independently controlled to regulate the speed of both the fan and stoker through the speed of the motor associated therewith.
- 35 40 As previously mentioned the particular design of stoker herein illustrated and described should not be considered as limiting the scope of the invention involved and as a consequence reservation is made to make such changes in 45 the essential and all of the nonessential details of the invention as may come within the purview of the accompanying claims.
- What I claim as my invention is:—
1. The combination with a wall of a stoker, 50 of a fuel feeding mechanism projecting from said wall at a point spaced from the lower edge thereof, a motor arranged adjacent said wall below said fuel feeding mechanism with the shaft thereof parallel with said wall, a 55 blower fan having a conduit connected to said wall and located to one side of said motor below said fuel feeding mechanism and having a driving connection with the shaft thereof, and means drivingly connecting the other 60 end of said motor shaft with said fuel feeding mechanism.
  2. In a stoker construction, the combination with a wall, of a fuel hopper adjacent the upper portion of said wall, fuel feeding 65 mechanism projecting forwardly from said

wall beneath said hopper and spaced upwardly from the lower edge of said wall, said fuel feeding mechanism including a reduction gear unit, a crank shaft connected thereto and a ram actuated by said crank shaft, a 70 blower fan and motor adjacent said wall in the space beneath said fuel feeding mechanism, the shaft of said motor being parallel with said wall and with said crank shaft, means operatively connecting said motor shaft to the reduction gear unit of said fuel feeding mechanism and to said fan, said fan and fuel feeding mechanism discharging through said wall.

3. In a stoker construction, the combination with a wall, of a fuel hopper arranged adjacent the upper portion of said wall, fuel feeding mechanism projecting forwardly from said wall beneath said hopper and spaced upwardly from the lower edge of said wall, a motor arranged adjacent said wall in the space below said fuel feeding mechanism, said motor having a shaft extending parallel to said stoker wall and beyond the motor at both sides thereof, a blower fan located to 90 one side of said motor below said fuel feeding mechanism and having a conduit discharging through said wall, means drivingly connecting one end of said motor shaft to said blower fan and means drivingly connecting the other end of said motor shaft to said fuel feeding mechanism.

4. In a stoker construction, the combination with a wall, of a fuel feeding mechanism projecting forwardly from said wall and spaced upwardly from the lower edge of said wall, said fuel feeding mechanism including a reduction gear unit, a crank shaft connected thereto and a ram actuated by said crank shaft, a blower fan and motor adjacent said wall below said fuel feeding mechanism, the shaft of said motor being parallel with said wall and with said crank shaft, means operatively connecting said motor shaft to the reduction gear unit of said fuel feeding mechanism and to said fan, said fan and fuel feeding mechanism discharging through said wall.

5. In a stoker, the combination with a wall, of fuel feeding mechanism projecting forwardly from said wall, a blower fan below said fuel feeding mechanism with the shaft thereof parallel with said wall, said fan having a conduit discharging through said wall, said fuel feeding mechanism and blower fan 115 being located adjacent to said wall and in the space defined by said wall and the vertical plane of the outer end of said fuel feeding mechanism, and a motor having means drivingly connecting the same to said fuel feeding mechanism and blower fan.

6. The combination with a stoker wall, of fuel feeding mechanism projecting forwardly from said wall, said fuel feeding mechanism including a reduction gear unit, a crank 130

shaft connected thereto and a ram actuated by said crank shaft, a blower fan adjacent said wall below said fuel feeding mechanism within the vertical space defined by the said wall and the vertical plane of the outer end of said fuel feeding mechanism and with the shaft thereof parallel with said wall, said fan having a conduit discharging through said wall, and a motor located within said space and having means drivingly connecting the same to said fuel feeding mechanism and blower fan.

In testimony whereof I affix my signature.

ROYCE L. BEERS.
